CLAIM

The ornamental design for a outdoor light, as shown and described.

DESCRIPTION

FIG. 1 is a front, top, left, perspective view of a first embodiment of an outdoor light showing my design therefor;

FIG. 2 is a front, bottom, left perspective view thereof;

FIG. 3 is a front elevational view thereof;

FIG. 4 is a rear elevational view thereof;

FIG. 5 is a right side view thereof;

FIG. 6 is a left side view thereof;

FIG. 7 is a top plan view thereof; and,

FIG. 8 is a bottom plan view thereof.

Throughout the drawings, broken lines show environment only and form no part of the claimed design.
